UNITED STATES PATENT OFFICE

RAYMOND E. DRAKE, OF BROCKTON, MASSACHUSETTS, ASSIGNOR TO AVON SOLE COMPANY, OF AVON, MASSACHUSETTS, A CORPORATION OF MASSACHUSETTS

DESIGN FOR A COMBINED SOLE AND HEEL FOR BOOTS, SHOES, OR SIMILAR ARTICLES

Application filed November 1, 1930. Serial No. 37,492. Term of patent 7 years.

To all whom it may concern:

Be it known that I, RAYMOND E. DRAKE, a citizen of the United States, residing at Brockton, in the county of Plymouth and State of Massachusetts, have invented a new, original, and ornamental Design for Combined Sole and Heel for Boots, Shoes, or Similar Articles, of which the following is a specification, reference being had to the accompanying drawing, forming part thereof.

In the drawings:

Fig. 1 is a view in side elevation of a shoe sole embodying the design.

Fig. 2 is a bottom plan view of the shoe sole.

Fig. 3 is a view in vertical cross section taken through the center line of the sole.

In the design as shown, the various ele-

ments 1 shown in white throughout the border of the heel and tread portions are narrow, raised ribs having convex surfaces, while the interposed elements 2 shown in black are depressed portions; the shank portion tapers slightly from the outer edges 3 to the line 4; the narrow borders 5 project slightly from the general surface of the heel and tread; and the elements 6 project still further from the general surface of the heel and tread.

I claim:

The ornamental design for a combined sole and heel for boots, shoes, or similar articles as shown and described.

In testimony whereof, I have signed my name to this specification.

RAYMOND E. DRAKE.
